DESIGN FOR A SIGN

Hyman C. Hammer, Chicago, Ill., assignor to Price Brothers, Inc., Chicago, Ill., a corporation of Illinois

Application March 17, 1937, Serial No. 68,210

Term of patent 3½ years

To all whom it may concern:

Be it known that I, Hyman C. Hammer, a citizen of the United States and resident of Chicago, in the county of Cook and State of Illinois, have invented a new, original, and ornamental Design for a Sign, of which the following is a specification, reference being had to the accompanying drawing forming a part thereof.

Fig. 1 is a front elevational view of a sign, embodying my invention.

Fig. 2 is a top plan view of the same.

I claim:

The ornamental design for a sign, substantially as shown.

HYMAN C. HAMMER.
